UNITED STATES PATENT OFFICE.

EDWY D. ENGLEDOVE AND CHARLES W. KITTERMAN, OF WASHINGTON, DISTRICT OF COLUMBIA.

SAFETY DEVICE FOR ELEVATORS.

1,164,796.

Specification of Letters Patent.

Patented Dec. 21, 1915.

Application filed August 5, 1908. Serial No. 447,050.

To all whom it may concern:

Be it known that we, EDWY D. ENGLEDOVE and CHARLES W. KITTERMAN, citizens of the United States, and residents of Washington, District of Columbia, have invented 5 a new and useful Safety Device for Elevators, of which the following is a specification.

Our invention relates to improvements 10 in safety devices for elevators, particularly that class known as door locking devices. Its design is to prevent the now frequent and often fatal accidents to passengers attempting to enter or leave an elevator while 15 the car is in motion.

The construction of our invention is shown in the accompanying drawings, in the different views of which similar characters refer to similar parts.

20 Figure 1 shows a form of the invention to be used when best suited to the construction of car and shaft. Fig. 2 shows an adaptation for use where the space at the side of the car is limited, or where this 25 form best meets the conditions as to construction of car and shaft. The principle of operation of the invention is the same in either case.

As shown in Fig. 1 a safety latch lever 30 D is pivoted at d' on the casing of the elevator shaft adjacent the side N of the door opening, and the inner end of this lever is connected by a link E to a locking lever B which is pivoted at b' to the casing and 35 has an inwardly projecting tooth b on its lower end adapted to engage a controlling member A on the elevator cage. To the outer side of the elevator cage is attached a controlling member or guard A, which is 40 simply a vertical bar attached to the side of the cage in position to come in contact with the tooth of the dog b on lever B, the ends of the member A being preferably rounded so that when the elevator rises 45 and falls the member A may engage and disengage the dog without shock. This member A has a notch A' which is located therein at such a point that when the floor

of the elevator cage is at the proper level with the floor of the landing the dog b 50 can enter the notch A'. The lever B is connected above pivot b' by a link C to the upper end of a controlling lever F which is pivoted to the casing at f adjacent the side N of the door opening, and in such position that its lower end will be engaged by the door N' when the latter is closed, so that lever F will be oscillated by the closing of the door and swing lever B so as to carry the dog b out of the notch A' in the controlling member A, and when the door N' 55 is closed and latched and locked—as by the usual catch n' engaging a keeper n on the casing—the parts will be in the position indicated in full lines in Fig. 1, so that the 60 dog b is held out of position to engage the member A. When the door N' is opened the lever B is pressed into position to engage with the member A by means of a spring S connected to the upper end of the 65 lever B and to a fixed point on the casing as shown. The spring actuated movement of the lever may be limited by a stop s . The door N' is provided with an auxiliary catch n^2 which when the door is closed will be 70 engaged by the tooth d of latch lever D as indicated in full lines in Fig. 1. The parts are so arranged and connected that the door N' can be slightly started outward before the tooth d and catch n^2 lock. If the elevator cage should be stopped either above 75 or below the proper floor level, then the dog b cannot enter notch A', but will be held out of locking engagement therewith, by member A, and therefore the latch lever D 80 will be held in position to engage catch n^2 on the door N'; and consequently though the operator may disengage the catch n' he 85 cannot open the door N', and the elevator cage must be shifted to the proper floor level—so that dog b can enter notch A' before the door N' can be opened. Upon closing the door N' lever F is oscillated thereby and shifts lever B so as to disengage dog b 90 from the notch A', and at the same time throw latch lever D downward into posi- 95

tion to cause dog d to engage catch n^2 , so that the door will be locked and remain locked until the elevator cage is again stopped in such position that the dog b can enter the notch A' . The door N' must be operated from within the car by the operator as usual, but he cannot open it until the cage is stopped at the right level. The car however can pass any landing without 10 affecting the safety locking devices of the door.

In the construction shown in Fig. 2, the lever B is arranged at one side of the door opening, but is connected to a bar C^2 , which 15 is slidably supported on the casing and has a lip C' on its free end adapted to be engaged by a stud or pin n^4 on the door N' , in closing, and be thereby moved so as to rock lever B and disengage the dog b from 20 notch A' so long as the door is closed as in dotted lines Fig. 2. A safety latch lever D^2 is pivoted to the casing adjacent the door opening and below bar C^2 , and is connected to the bar C^2 by a link E^2 . Said lever D^2 25 has a head d^3 adapted to drop behind a pin n^5 on the door N' when the door is closed (see dotted lines Fig. 2), and will prevent opening of the door unless the elevator cage is stopped in such position (as 30 shown in full lines Fig. 2) that dog b can engage notch A') in the member A . The door N' is shown closed in dotted lines in Fig. 2, and when the door starts to open the pin n^5 will engage head d^3 of lever D^2 unless tooth b can enter notch A' . If tooth b finds notch A' then lever D^2 rises to the 35 position shown in full lines Fig. 2 before pin n^5 strikes it thus letting the door open freely. When the door closes after pin n^5 40 passes the head d^3 , pin n^4 engages lip C' and causes lever B to disengage member A , and head d^3 to drop behind pin n^5 , the parts operating substantially as the parts in Fig. 1.

45 When the car is to be stopped at a landing, the operator must bring its floor practically flush with the floor of the building (the amount of the tolerance will be determined by the length of the recess in the controlling member) so that the pawl can drop into the recess, before the door can be opened. The pawl should be of substantial construction to resist shock, but as there will be no great strain upon any of the other parts, they 50 may be made of lighter material.

A peculiar advantage of our invention is that its action is not dependent upon the thought of the elevator conductor. It works without receiving any attention from him; 60 he simply goes through the usual motions required in operating the car. The door can not possibly be opened until the car has been brought to a standstill at a floor landing; and when the car has been stopped and

the door opened, it is automatically locked 65 and held until the door is again closed.

The double door system is not an absolute safeguard against accident through carelessness on the part of the elevator operator or the passenger. The operation of the inner 70 door is not automatic, but is dependent upon the will of the conductor. Our device works satisfactorily on the inside doors, and if used on them absolutely prevents accidents of the character mentioned. However, if 75 the invention is applied to the outer door, there is no need of the inside door at all.

What we claim as new and desire to secure by Letters Patent is:

1. In a safety attachment for elevator 80 shaft casing doors, the combination of a car, a notched controlling member moving with the car, and a landing door; with a locking dog pivoted on the shaft casing adjacent said door, a device adapted to be actuated 85 by the door, whereby the dog is held out of engaging position while the door is closed, a safety lever pivoted on the casing, a link connecting said lever with the door actuated device, and a device on the door 90 engaged by said safety lever whereby the door is kept locked until the controlling member is properly positioned opposite the dog.

2. In a safety attachment for elevator 95 shaft doors, the combination of a car, a notched controlling member moving with the car, a landing door, a locking dog pivoted on the shaft casing adjacent said door, a member adapted to be actuated by the 100 door and whereby the dog is held out of engaging position while the door is closed, a safety lever, and a device on the door engaged by said safety lever whereby the door is kept locked until the car is properly positioned opposite the door, and connections between the safety lever and the locking dog, substantially as described.

3. In combination, an elevator cage, a locking member on the cage, a shaft door, 110 and a catch on the door; with a cage locking device in the shaft adjacent the door adapted to engage the member on the cage; a door-locking device in the shaft adapted to engage the catch on the door, and connections between the cage-locking device and the door-locking device whereby when one is in locked position the other is in unlocked 115 position, and means for releasing the said door-locking device when the shaft door is 120 opened.

4. The combination with an elevator cage, a notched member on the cage, a shaft door, and a catch on the door; of a cage locking lever in the shaft adapted to engage the 125 notch in the member on the cage; a door-locking lever pivoted in the shaft in position to engage the catch on the door when

the latter is closed, connections between the cage-locking lever and the said door-locking lever whereby when one is in locked position the other is in unlocked position, and 5 means for releasing the said door-locking lever when the shaft door is opened, substantially as described.

In testimony whereof we have hereto

signed our names in the presence of two subscribing witnesses.

EDWY D. ENGLEDOVE.
CHARLES W. KITTERMAN.
